CLOSURE OPERATING MEANS

Filed March 29, 1928

UNITED STATES PATENT OFFICE

OSCAR VANDERZEE, OF HAWTHORNE, NEW JERSEY

CLOSURE-OPERATING MEANS

Application filed March 29, 1928. Serial No. 265,563.

The object of this invention is to provide simple and reliable means whereby a door or doors of a garage or the like may be operated by a vehicle as an incident of its movement on approaching or leaving the same. To this end I provide an actuator, as an overhead rail movable lengthwise of the path of the vehicle, suitably connected with the doors, and on the vehicle a suitable abutment for engaging the actuator and causing its movement. In the best construction the actuator is movable back and forth, in one direction to open the doors and in the other to close them, the whole system moving to a definite limit in each direction, and in order that the vehicle may pass clear of the actuator when such system is at either limit suitable provision is made as will appear.

In the drawing, Fig. 1 is a vertical longitudinal section of a garage with my mechanism and the vehicle in side elevation and showing (in full lines) the vehicle about to leave the garage, whose doors are closed, the dotted lines showing the positions assumed by the parts when the vehicle has left the garage;

Fig. 2 is a horizontal section of the garage with my mechanism and the vehicle in plan, the parts appearing in full lines the same as they appear in full lines in Fig. 1; and

Figs. 3 and 4 are side and front elevations, partly in section, of a detail.

1 designates the garage and 2 the hinged doors thereof movable to closed position against a stop 3 and to open position to a limit to be indicated.

In suitable overhead hangers 5 arranged in alignment lengthwise of the garage is slideable longitudinally back and forth the actuator 6, being here a rail; the hangers may be secured to any part of the overhead structure of the garage and to afford proper support for the outer end of said actuator, which when in its outer position projecting appreciably from the garage as shown, one such hanger may be attached to a fixed beam 7, itself projecting from the garage. This rail has, one inside and the other outside the garage, depending catches 6^a, formed say of metal and suitably secured to the rail. Links 8 pivotally connect

the respective doors with a stud 9 on the rail. The vehicle may have some abutment, as a cross-bar 10 fixed at a suitable elevation above its roof in bracket 11, to engage the catches. Either this abutment or the catches should be 55 yielding; in the example, I make the latter yielding by forming them flexible and elastic.

The links 8 are of such length that when the doors are fully open to the limit afforded by the links each link is substantially perpendicular to the rail, so that each door is locked against moving closed under wind pressure.

Preferably the rail has means to limit its movements, as the stop 4^a against which its rear end may abut when it moves inward and 65 the stop 4^b against which a projection 6^b on the rail abuts when the rail moves forward, stops 4^b and 6^b being so positioned as to abut each other when the doors have reached their outer limit.

Movement of the actuator inwardly closes and movement thereof outwardly opens the doors, as will be obvious. Therefore, on movement of the vehicle *a* in either direction, if the system including the doors, links and 75 actuator has been previously moved in the relatively opposite direction to the limit, the vehicle (by engagement of bar 10 with one of the catches) will move the system in relatively the same direction as it is moving; 80 when the vehicle must pass either catch at the time said system has been moved to its limit in the same direction as the vehicle is moving the catch yields under the pressure of the bar 10, springing back to normal position when the bar clears it. In leaving the garage therefore, the vehicle in moving back would open the doors and having passed first the inner catch and then the outer one, to close the doors the vehicle would be sufficiently returned so that by engagement with the outer catch the closing would result; in entering the garage the vehicle would be advanced till bar 10 passed the outer catch and then returned to open the doors and then advanced 85 again till bar 10 engaged the inner catch and closed the doors.

Figs. 3 and 4 show the catches adjustable to different positions along the rail. A strip of metal to form each catch has a hook at 12 100

and the end of the strip rebent to form a head and a bolt 14 removably received in any of the holes 14^a supports the catch as shown with its head bearing squarely against the top of the (channel) rail. Fig. 4 shows also rollers 5^a on the hangers affording anti-friction bearings for the rail.

In the appended claims, the expression "support having a vehicle opening therethrough" is in the example the garage structure here including the beam 7 and also having as said opening that of which the doors form the closures and through which the vehicle as described enters and leaves the garage.

Having thus fully described my invention, what I claim is:

1. In combination, a support having a vehicle opening therethrough, a closure pivotally movable to close or leave open said opening, and means, including an actuator slideable back and forth in the support longitudinally of itself and confined to slide in a definite path lengthwise of the path of travel of a vehicle through the opening, and a link pivotally connecting the closure and actuator, for moving the closure to one of its open or closed positions, said link being substantially perpendicular to the actuator when the closure is open.
2. In combination, a support having a vehicle opening therethrough, a closure movable back and forth to close or leave open said opening, in one direction to a definite limit, and means, movable in said support by the vehicle, for moving the closure to said limit, said means and vehicle having catching portions stiffly projecting therefrom engageable with each other to cause such movement of said means and one of which is elastic and yieldable to the other to permit the vehicle to clear said means on movement of the closure to said limit.
3. In combination, a support having a vehicle opening therethrough, a closure movable back-and-forth to definite limits to close or leave open said opening, and means, including an elongated stiff actuator slideable back-and-forth in the support lengthwise of itself and of the path of travel of a vehicle through the opening, and having catching means stiffly projecting therefrom inside and outside of the opening, for moving the closure to either limit, said vehicle also having a catching means engageable with said catching means of the actuator, and the catching means of the actuator and vehicle being elastic and yieldable one relatively to the other.

In testimony whereof I affix my signature.

OSCAR VANDERZEE.
